[57] CLAIM

The ornamental design for a heart-shaped lip balm case, as shown and described.

DESCRIPTION

FIG. 1 is a top front right perspective view of the heart-shaped lip balm case showing my new design thereof;

FIG. 2 is a top plan view thereof;

FIG. 3 is a right-side elevational view thereof;

FIG. 4 is a left-side elevational view thereof;

FIG. 5 is a front elevational view thereof;

FIG. 6 is a rear elevational view thereof;

FIG. 7 is a bottom plan view thereof; and

FIG. 8 is a top front right perspective view of a second embodiment of my new design;

FIG. 9 is a top plan view of the second embodiment;

FIG. 10 is a right-side elevational view of the second embodiment;

FIG. 11 is a left-side elevational view of the second embodiment;

FIG. 12 is a front elevational view of the second embodiment;

FIG. 13 is a rear elevational view of the second embodiment; and,

FIG. 14 is a bottom plan view of the second embodiment;
